(57) **CLAIM**

The ornamental design for a forestock, as shown and described.

DESCRIPTION

FIG. 1 is a back, top, left side perspective view of a forestock, showing my new design with support legs in a first position.

FIG. 2 is a front elevation view thereof.

FIG. 3 is a back elevation view thereof.

FIG. 4 is a right elevation view thereof.

FIG. 5 is a left elevation view thereof.

FIG. 6 is a top view of the embodiment thereof.

FIG. 7 is a bottom view thereof.

FIG. 8 is a back, top, left side perspective view of a forestock, showing my new design with support legs in a second position.

FIG. 9 is a front elevation view thereof.

FIG. 10 is a back elevation view thereof.

FIG. 11 is a right elevation view thereof.

FIG. 12 is a left elevation view thereof.

FIG. 13 is a top view thereof; and,

FIG. 14 is a bottom view thereof.

The dashed lines in the figures do not form any part of the design sought to be patented.
